UNITED STATES PATENT OFFICE.

ACHILLES DE KHOTINSKY, OF CHICAGO, ILLINOIS.

ELECTRIC HAMMER.

1,110,447.

Specification of Letters Patent.

Patented May 25, 1915.

Application filed June 10, 1907. Serial No. 378,126.

To all whom it may concern:

Be it known that I, ACHILLES DE KHOTINSKY, a citizen of the United States, residing in Chicago, in the county of Cook and State 5 of Illinois, have invented a new and useful Improvement in Electric Hammers, of which the following is a specification.

My invention relates primarily to portable electrically actuated hammers; and it has 10 for its primary object the production of an electric hammer of maximum efficiency and minimum weight and bulk, and for further objects the effecting of all other improvements in construction and function that are 15 found to obtain in the devices hereinafter described or claimed.

In the electric hammer hereinafter set forth, there is no recoil against the hand of the operator, the retracting stroke of the 20 core being magnetically cushioned; the character and arrangement of the magnetic fields is designed to avoid overheating of the device, and to this end the magnetic circuits are balanced in such relation as tends to 25 their special efficiency for the intended work; for increasing the strength of the blow struck, the maximum magnetic energy is concentrated at the instant of impact of the percussion core; for increasing the frequency of blows, it is sought to make the 30 retracting action especially efficient and to make the current shift and reversal as nearly instantaneous as may be; provision is made for varying at will the force of the blow; 35 and the entire controlling mechanism is self-contained within the portable machine-tool itself and is designed to be automatic and mechanically positive in action.

In the accompanying drawings forming 40 a part of this specification, Figure 1 is a central longitudinal section through the complete device, with the reversing and controlling mechanism shown partly in elevation; Fig. 2 is a section on the line 2—2 of Fig. 1; Fig. 3 is a section on the line 3—3 of Fig. 1; Fig. 4 is a partial view similar to Fig. 1 but enlarged; Fig. 5 is a section on the line 5—5 of Fig. 1; Fig. 6 is a vertical section through the current diverter, taken 50 on the line 6—6 of Fig. 4; Fig. 7 is a diagrammatic view of the complete electrical circuits and showing the conditions of electrical and magnetic energization as the core approaches, but before it reaches, the limit 55 of its driving stroke; Fig. 8 is a similar diagrammatic view of the electrical cir-

cuits of the driving electro-magnet, and shows the conditions of electrical and magnetic energization at the instant when the core begins its driving stroke, and also indicates, by the curve K, K, the acceleration 60 of the core moving under the influence of the progressive augmentation of the magnetic pull drawing the core into the driving coils during the driving stroke; and Fig. 9 is 65 a similar diagrammatic view of the electrical circuits of the retracting electro-magnet, and shows the conditions of electrical and magnetic energization at the instant when the core begins its retracting stroke, 70 and also shows, by the curve L—L, the initial acceleration and subsequent retardation of the core moving under the influence of the progressively diminishing magnetic pull drawing the core into the retracting 75 coils during the retracting stroke, such action constituting the magnetic cushioning of the core at the limit of its retracting stroke.

Like reference numerals indicate like 80 parts in all of the figures.

10 is the reciprocating core, of magnetic material, adapted to freely reciprocate within the core tube 11 and to percussively strike the blow-transmitter 12, which is of magnetic material. The said core-tube is of non-magnetic material, and is longitudinally slotted, at 13, to prevent magnetic induction, and upon it are wound a series of three successive coils of insulated wire, 14, 15 and 16. These three coils, of equal length, are all direct-wound, or wound in one direction, and permanently connected end to end with each other, at the loops 17 and 18, by virtue of the fact that they are one continuous uniformly wound wire; so that said three coils are in effect one continuous coil sectionally wound, in three sections, with the permanent connecting loops tapped by the conductors that will be hereafter specified. Between the adjacent ends of these three coils are the disks of magnetic material 19 and 20, and in contact with the outside periphery of these disks and closely enclosing the coils is the casing of magnetic material consisting in the shell 21 and end plate 22. The coils thus inclosed by the magnet-casing and disks, and being thus jacketed both outside and at both ends with magnetic material, constitute, when electrically energized either singly or in series, 100 electro-magnets of the type known as "iron- 105 110

clad," which have a maximum efficiency, in proportion to the amount of wire used, by reason of the shortening of the magnetic circuit between the attracted end of the core 5 and the attracting pole of the electro-magnet. The series of coils are electrically energized in pairs, the end coil 14 and middle coil 15 to produce the effect of retracting the core, and the middle coil 15 and other 10 end coil 16 to produce the effect of driving the core; and these pairs of coils, thus electrically energized, constitute, in conjunction with the core and their inclosing magnetic casing and disks, two alternately acting electro-magnets, one for retracting and the other for driving the percussion-core. The retracting magnet includes the electrically energized end coil 14 and middle coil 15 and the inductively energized casing 21, 15 end-plate 22 and disk 20,—the disk 19, intermediate the two said coils 14 and 15, being neutral at the instant when the two said coils are fully energized. The driving magnet includes the electrically energized middle coil 15 and other end coil 16, and the inductively energized casing 21, disk 19 and blow-transmitter 12,—the disk 20, intermediate the two said coils 15 and 16, being neutral at the instant when the two said 20 coils are fully energized.

The current from one, say the positive, pole of the source of electric energy, which may be the ordinary city power, enters the end coil 16, from the connection 23, at the terminal 24, when the driving field is energized, and, traversing said coil 16, passes over into the middle coil 15, through the loop connection 18, and traversing said middle coil 15 leaves it through the connection 25, tapping loop 17, and thence proceeds to the other or negative pole of the source of energy. When the retracting field is energized, the current from the aforesaid positive pole of the source of energy enters the other end coil 14, the fundamental coil of the retracting magnet, from the connection 26, at the terminal 27, and traversing said coil passes over, through the loop connection 17, into the middle coil 15, and traversing 30 the latter coil leaves it through the connection 28, tapping loop 18, and thence returns to the negative pole of the source. The aforesaid connection 23, entering the negative terminal of the driving-magnet coils, leads from the positive driving-magnet contact 29; and the connection 25 leads from the positive terminal of the driving-magnet coils to the negative driving-magnet contact 30. The connection 26, entering the negative terminal of the retracting-magnet coils, leads from the positive retracting-magnet contact 31; and the connection 28 leads from the positive terminal of the retracting-magnet coils to the negative retracting-magnet contact 32. The current 35

entering the two aforesaid positive contacts and leaving the aforesaid negative contacts traverses the upper and lower members, respectively, of the two-part oscillating diverter, or contact maker-and-breaker, 33, 70 which is secured to the rock shaft 34 journaled at 35 and 36 in opposed walls of the diverter-box 37. The current from the source of energy enters the one member of said diverter from the positive constant contact 38, and leaves the other member of said diverter, to return to the source, through the negative constant contact 39. The connection 40, entering the positive constant contact, leads from the negative side of the spring switch-contact 41, the current being conveyed to the positive side of said spring switch-contact, from the source of energy, by the wire 42 entering the hole 43 in handle 44. The current leaving the negative 85 constant contact 39 returns to the source through the wire 45 passing out through the aforesaid hole 43. The plunger 46, operated by means of the thumb-knob 47, makes and breaks the circuit between the poles of 90 the aforesaid switch-contact 41, at the will of the operator.

The positive and negative constant contacts 38 and 39 are located side by side in the same radial position with respect to the center of oscillation of the diverter 33 (see 95 Figs. 4 and 6), and are in constant sliding contact with the broad arms of the right-hand and left-hand members (as seen in Figs. 2 and 6), respectively, of the said 100 diverter. The opposed narrow arms of the said members of the said diverter are adapted to make contact with the contacts of the driving-magnet and the contacts of the retracting-magnet in alternation. The said 105 positive and negative driving-magnet contacts, 29 and 30, are side by side in the same radial position, and respectively arranged to make contact with the said right-hand and the said left-hand members, respectively, of 110 the diverter; and the positive and negative retracting-magnet contacts, 31 and 32, are side by side in another radial position, and similarly adapted to make contact with the respective members of the diverter. And 115 the radial or angular separation of the pair of driving-magnet contacts from the pair of retracting-magnet contacts is such that the narrow arms of the diverter-members will a little more than span the space, so that as 120 the diverter oscillates, its contact with the driving-magnet contacts, 29 and 30, is not broken until its contact with the retracting-magnet contacts, 31 and 32, is made, and vice versa; with the result that there is substantially no sparking between the diverter and any of the said contacts and the current is substantially constant. The total 125 electrical energization of the coils thus remains substantially constant, while its dis- 130

tribution and direction change. When the diverter is at one limit of its oscillatory movement, its right-hand member makes the connection between the source of current and the positive driving-magnet contact 29, and its left-hand member makes the connection between the negative driving-magnet contact 30 and the source of energy; and at the other limit of its oscillation, the right-hand member of said diverter makes the connection between the source of energy and the positive retracting-magnet contact 31, and its left-hand member makes the connection between the negative retracting-magnet contact 32 and the source of energy. And when the diverter is in intermediate position, its right-hand member makes connection between the source of energy and the positive contacts of both the driving and the retracting-magnets, and its left-hand member makes connection from the negative contacts of both the driving and the retracting-magnets back toward the source of energy. All of the aforesaid contacts 29, 30, 31, 32, 38 and 39 are quadrilateral carbons freely held in sockets secured in the insulation material forming the opposed walls 48 and 49 of the diverter-box; and each carbon is constantly pressed outward by a spiral spring within its socket. The contact-making members of the diverter 33 are surrounded by bushings 50, 50 of insulation material, and this bushing is so extended, at 72 (Figs. 2 and 4), on either side of the narrow arms of the diverter-members as to engage and retain in their sockets the carbons of the contacts released by the said diverter arms at either limit of the diverter's oscillation.

It is apparent that the oscillation of the diverter effects the shifting of the electric energization from the driving electro-magnet to the retracting electro-magnet, with the consequent shifting of the magnetic fields influencing the movements of the core; and it is also apparent that the connections between the diverter-contacts and the respectively reversed terminals of the two said electro-magnets, are such that as the current shifts from the driving-magnet to the retracting magnet, the direction of the electrical energization will be reversed, thereby effecting the hereinafter considered demagnetization and reversal of polarity of the core and of the blow-transmitter 12.

To automatically oscillate the diverter, by direct mechanical connection with the successive movements of the core, there is provided a stop-rod 51 working freely in an aperture 52 extending axially through said core, the said stop-rod being provided with opposed stops 53 and 54 and connected to the middle of the lever 55, the said lever being pivoted at one end to a fixed stud 56, 65 projecting from the inner wall of the di-

verter-box, and being connected at its other end, by the connecting rod 57, to the diverter itself. Within the stops 53 and 54 respectively are arranged the cushioning stop-springs 58 and 59, adapted to engage and be compressed by the respectively opposite ends of the core at or near the limits of its reciprocating movement. The ends of the core are recessed, at 60 and 61, to accommodate these springs as the core-ends approach the respectively opposed stops; and the blow-transmitter 12 is recessed at 62 to accommodate and protect the stop 54 as the percussion-end of the core approaches and strikes the inner face of said blow-transmitter. As the core approaches the limit of its driving stroke it meets and compresses the corresponding stop-spring 59 until the resistance of said spring overcomes the frictional resistance of and moves the oscillating diverter 33, thereby shifting the electrical energization from the driving-magnet into the retracting-magnet and producing the reversal of movement of the core; and as the core approaches the limit of its retracting stroke it engages and compresses the stop-spring 58 until the resistance of said spring overcomes the resistance of and moves the oscillating diverter in the opposite direction, thereby shifting the electrical energization from the retracting into the driving magnet and causing the reversal of the movement of the core to effect the driving stroke.

To carry the diverter as instantaneously as possible over the interval between the contacts of the driving-magnet and the contacts of the retracting-magnet, one end of the diverter's rock-shaft 34 has secured to it, at right angles to the axis of the diverter, a crank-arm 63 upon which is looped the spring 64 whose other end is secured to the stud 65 projecting from the side wall of the diverter-box. As the core strikes either stop-end of the stop-rod 51, the resulting initial movement of said stop-rod stretches, or stores power in, said spring 64, and then as the member 63 moves on far enough to release it, this spring, by its sudden retraction, or discharge of its stored power, will act to jerk the said crank-arm ahead and snap the diverter to the other limit of its range of oscillation. This spring-trigger action, snapping the diverter ahead with the spring-power stored by the initial impulse that the core gives the stop-rod, accelerates and insures the oscillatory movement of the diverter, inasmuch as the core is not sufficiently attracted in either direction when the diverter is intermediate the contacts of the driving and the retracting-magnets; and except while shifting from one to the other, the diverter is positively and mechanically detained at one or the other of its said contact positions, by reason of the fact that the

crank-arm 63 is thrown over its center of oscillation and so retained by the spring 64 until the positive movement of the stop-rod by the core shifts said crank-arm over to the opposite limit of its path of oscillation. To control the force of the impact or percussion of the core upon the blow-transmitter, and to gradually increase such force of impact as the operator puts the hammer into action, the entire diverter mechanism, contained in the diverter-box, is made movable to and from the electro-magnets, so that the stop-rod 51, connected to the lever 55 in the diverter-box, may be advanced or receded, through the core, to bring the stop 54 and stop-spring 59 nearer to or farther from the extreme possible limit of the driving stroke of the core. The farther the said stop and stop-spring from the said limit, the sooner they are engaged by the percussion-end of the core and the sooner the consequent reversal of the core's movement. If this reversal occurs soon enough, the percussion-end of the core will be magnetically cushioned and checked before it reaches or strikes the blow-transmitter, and no blow will be struck. If the reversal is then slightly deferred, the core may reach and lightly strike the blow-transmitter; and as the reversal is still further deferred, the impact of the core upon the blow-transmitter will be increased to its possible maximum. This optional movement of the diverter-box is effected by adapting the lower end of said box to slide on the prolonged upper end of the core-tube 11, and by providing a stud 66 projecting upward from the top of said diverter-box and adapted to be engaged by the middle part of the swinging-lever 67 that is pivoted, at 68, to the inner wall of the handle and that carries the thumb-knob and plunger, 47—46. The sliding diverter-box is radially positioned by the fixed centering-pin 69, passing through a hole in the bottom wall of the box, and is normally held in its outer or retracted position by the spiral spring 70. And the swinging-lever 67 is normally held in its upper or raised position by the spiral spring 71 surrounding the end of stud 66. As the operator depresses the thumb-knob 47 the plunger 46 first closes the circuit in the switch-contact and the reciprocatory movement of the core commences, and at the same time the middle of the swinging-lever 67 engages the top of the diverter-box stud 66 and commences the depression of said diverter-box toward the electro-magnets. At first the reversal of the core at the end of its driving stroke may occur before the core meets or strikes the blow-transmitter, and then as the thumb-knob 47 is still further depressed, causing the diverter-box to be pressed down nearer and nearer to the electro-magnets, the aforesaid reversal of

the core is more and more retarded so that the blows upon the blow-transmitter become harder and harder and finally reach the maximum when the operator has completely depressed the thumb-knob. Thus this sliding mounting of the diverter-mechanism within the handle casing makes it possible to bring the stroke of the core operatively against the blow-transmitter at any desired point in said stroke, within the limits of such sliding adjustability of the diverter-mechanism. The large coiled spring 70 normally holds the parts in such relation that the core strikes the blow-transmitter lightly, and as said spring is forcibly compressed it permits the relation of the parts to be so changed that the transmitter is struck harder and harder, the instant of impact of the core, with said transmitter, becoming progressively earlier relatively to the instant of reversal of the core's movement.

The tool-end or blow-transmitter being of magnetic material and all of the parts above the opposite end-plate 22 being of non-magnetic material, the aforesaid retracting magnet becomes of the "open" iron-clad type, since both ends of the core-tube of said magnet are open, and the aforesaid driving magnet becomes of the "stopped" iron-clad type, since one end of the core-tube of said magnet is stopped with magnetic material; wherefore the large mass of magnetic material in the blow-transmitter is energized as an attracting pole of the driving magnet, and the magnetic circuit from the percussion-end of the core to the attracting pole of the driving electro-magnet is shortened to the straight distance between the said core-end and the inner or struck face of the blow-transmitter, while the magnetic circuit between the other end of the core and the attracting pole of the retracting electro-magnet would be represented by a curve from the said core-end to the inner wall of the relatively thin magnetic end-plate 22. As a result of this distribution of magnetic fields and lines of force, the magnetic attraction between the core and the opposed pole in the stopped end of the driving electro-magnet, while the latter is electrically energized, rises to a very abrupt and steeply peaked maximum as the core plunges toward the blow-transmitter 12, producing the acceleration of movement diagrammatically indicated by the curve *k* in Fig. 8, so that the impelling force is concentrated close to the point of impact; while the magnetic attraction between the core and the opposed or attracting poles of the retracting electro-magnet, while the latter is electrically energized, is initially accelerated to a maximum and gradually falls off to zero as the core approaches and reaches the end-plate 22, producing the initial acceleration and sequent retardation of movement diagram-

matically indicated by the curve L in Fig. 9, so that the retracting force is distributed in gradually diminishing measure and the core is magnetically cushioned within its re-tracting stroke and does not tend to have its upper end thrown above the aforesaid end-plate 22. In this manner there is attained the maximum efficiency of blow upon the tool-end or blow-transmitter 12, and yet no back stroke or consequent recoil is produced in the retracting of the core after each working blow struck. The general principle that controls the increased effectiveness, for their respective purposes, of the "open" and "stopped" iron-clad magnets above described, is twofold. First:—that the shorter the air gap or circuit between the attracted end of the core and the attracting end of the electro-magnet, the greater the number of lines of magnetic force there will be within the length of the said air-circuit, and the greater the consequent intensity of the magnetic attraction; and this applies equally to the relation between the other end of the core and the corresponding opposite pole of the active magnet during the retracting action and the driving action respectively,—that is to say, during the driving action, the magnetic circuit from the upper part of the core to the upper pole of the driving magnet is shortened to the distance from such part of the core to the inner wall of the magnetic disk 19, while during the retracting action, the magnetic circuit from the lower end of the core to the lower pole of the retracting electro-magnet is shortened to the distance between the said part of the core and the inner wall of the magnetic disk 29. Second:—that the mass of magnetic material in the magnetic "stopper" of the "stopped" iron-clad magnet concentrates the lines of magnetic force near said stopped end of the driving magnet; while the uniform magnetic jacket of the "open" retracting magnet distributes such lines in gradually decreasing concentration along the whole air-gap from the core to the open retraction end of said magnet, the disk 22. The magnetic pull driving the core vanishes abruptly from a maximum, when the core strikes the blow-transmitter 12; but the magnetic pull retracting the core vanishes gradually as the core approaches and reaches the disk 22.

From the foregoing, it is obvious that the field of the retracting magnet and the field of the "driving" magnet, respectively indicated as *b-b* and *c-c* in Fig. 7, are half superposed on each other, because, while the end coil 14 is only energized during the retracting action and the other end coil 16 is only energized during the driving action, the middle coil 15 is common to both and is electrically energized, during the action of both.

And the core is substantially of the length of two of the coils, so that at the end of its driving stroke it just completes the magnetic axis of the driving magnet, and at the end of its retracting stroke it becomes and just equals the substantially-balanced magnetic axis of the retracting magnet. The equality of the two end coils with each other, and of each with the middle coil, in the magnets having thus superposed fields, permits the utilization, in each stroke, of the maximum possible proportion, two-thirds, of the total possible efficiency of the entire series of three coils, and at the same time permits each of the end coils to be used at its own highest possible efficiency, as limited by the winding, without superheating either, as each offers the same resistance to the same current. The above-described partial coincidence or mutual superposition of the fields of the two magnets upon each other effects the greatest possible compactness of construction and saving of weight and material because of the two-fold utilization of the one middle coil 15 and also by reason of the fact that the magnetic disks 19 and 20, which are alternately neutral when occupying the positions intermediate the energized coils, become in alternation the like magnetic poles of the alternately and reversely energized electro-magnets and make each of said magnets completely and uniformly iron-clad. The partial superposition of the two magnetic fields, by making the middle coil common to both the retracting and the driving magnets, and the reversal of the current for the retracting action, further effects the demagnetization of the blow-transmitter 12, and reversal of the polarity of the core, at the end of the driving stroke. As the core is of hardened magnetic material, preferably steel, it becomes polarized during each stroke, and at the end of the driving stroke would tend to remain permanently attracted and held to the struck face of the blow-transmitter 12. The demagnetization necessary to prevent this holding or sticking of the core is effected by reversing the direction of the electrical energization or current as the said energization is shifted from the driving magnet into the retracting magnet, so that the polarity of the core and of the magnet-easing of the coils will be reversed, neutralizing the residual polarity of the blow-transmitter that constitutes the magnetic "stopper" of the "stopped" end of the iron-clad driving-magnet and inducing some reverse polarity in the core somewhat in advance of the demagnetization and reversal of polarity of the blow transmitter,—the blow-transmitter being remote from the field of the retracting coils and only feebly influenced by the leakage from such field through the casing of end coil 16, while on the contrary the core is half within said field, the blow-transmitter resists demagnetization.

longer than the core. The demagnetization and reversal of polarity of the core, slightly before the reversal of polarity of the blow-transmitter, of course produces an instant 5 re-pulsion between the blow-transmitter and the adjacent end of the percussion core, thereby permitting said core to be retracted by, or even repelling it toward, the field of the re-tracting magnet. By reason of this reversal 10 of the direction of the electrical energization, it is obvious that while the current will always be in one direction in the end coil 16, the fundamental coil of the driving magnet, and will always be in the opposite direction 15 in the other end coil 14, the fundamental coil of the retracting magnet, it will be alternately first in the one direction and then in the other in the middle coil 15, when the electric energization fully occupies first the 20 driving field and then the retracting field respectively, and will be substantially neutral in said middle coil 15, for an instant intermediate the two limits of the shifting of the energization from the one field to the 25 other. During this last mentioned instant of neutral condition in the middle coil the magnetic influence acting upon the core will be transferred from one to the other of the end coils 14 and 16, and as soon as the electric 30 energization of the middle coil is actually reversed in direction, said middle coil, always inclosing a half part of the core 10, will directly exert its influence upon said core to further the required demagnetization 35 and reversal of polarity thereof. And the aforesaid superposition of the retracting and the driving magnetic fields, has a still further function in facilitating the use of a substantially constant uninterrupted electrical 40 current, gradually, instead of abruptly, shifted from the one field of energization into the other without substantial break or interruption in the magnetic control of the core, there being a progressive 45 reduction of electric current in the end coil 16 as the electric energization shifts into the retracting field, and, vice versa, a gradual reduction of electric current in the other end coil 14 as the electric energization shifts into 50 the driving field, as more fully appears in the foregoing description of the connections between the source of current and the series of coils.

My invention is hereinabove set forth as embodied in a particular form of construction, but I do not limit it thereto or to less than all the possible forms in which the said invention as hereinafter claimed may be embodied and distinguished from prior devices for like purposes.

I claim:—

1. In an electric hammer, in combination: a reciprocatory magnetic percussion-core within, and itself about two-thirds the length of, three axially alined and contigu-

ous equal coils adapted to be alternately energized in series in pairs; a peripheral, end and intermediate jacketing of magnetic material, constituting said coils ironclad; connections of one polarity leading to the free ends of the end coils, and of opposite polarity tapping the connections between the middle and end coils, whereby the coils may be energized in pairs to produce in alternation a driving and a retracting motor-magnet of reverse polarity and having a half-part of their fields superposed; a blow-transmitter of magnetic material at the impact end of the driving magnet, constituting said magnet of stopped type, the retracting magnet being of open type; automatic diverter-mechanism, self-contained in the device, for diverting the current alternately from one field to the other, said mechanism being mechanically controlled by the reciprocating core and having an oscillating diverter adapted to be shifted to the alternately active contacts and to span the space between them, and a stop-rod co-operating with said diverter and freely inserted longitudinally through the core and provided with opposed stops and with opposed cushioning means to cushion the movement of said stop-rod, and a spring-trigger mechanism for snap-shifting the diverter and for detaining the diverter at either limit of its throw; and optionally operable means for graduating the impact of the core upon the blow-transmitter, said means including a slidably movable member, for approximately the point of impact and the diverter mechanism, and a coil spring normally holding the parts in such relation as to give the lighter impact but compressibly yielding to permit heavier impact; substantially as specified.

2. In an electric hammer, in combination: a reciprocatory magnetic percussion-core reciprocating within, and itself about two-thirds the length of, three axially alined and contiguous equal coils adapted to be alternately energized in series in pairs; and connections whereby the coils may be energized in pairs to produce in alternation a driving and a retracting motor-magnet of respectively completely reverse polarity and having a half-part of their fields superposed in respect to the successive positions thereof; substantially as specified.

3. In an electric hammer, in combination: a reciprocatory magnetic percussion-core reciprocating within three axially alined and contiguous coils adapted to be alternately energized in series in pairs; and connections of one polarity leading to the free ends of the end coils, and of opposite polarity tapping the connections between the middle and end coils, whereby the coils may be energized in pairs to produce in alternation a driving and a retracting motor-magnet of

respectively completely reverse polarity and having a half-part of their fields superposed in respect to the successive positions thereof; substantially as specified.

- alternately energized in series in pairs; a peripheral end and intermediate jacketing of magnetic material, constituting said coils ironclad; connections of one polarity leading to the free ends of the end coils, and of opposite polarity tapping the connections between the middle and end coils, whereby the coils may be energized in pairs to produce in alternation a driving and a retracting motor-magnet of respectively completely reverse polarity and having a part of their fields superposed in respect to the successive positions thereof; and a blow-transmitter of magnetic material at the impact end of the driving-magnet, constituting said magnet of stopped type, the retracting magnet being of open type; substantially as specified. 70
13. In an electric hammer, in combination: a reciprocatory magnetic percussion-core reciprocating within three axially alined and contiguous coils adapted to be alternately energized in series in pairs; connections of one polarity leading to the free ends of the end coils, and of opposite polarity tapping the connections between the middle and end coils, whereby the coils may be energized in pairs to produce in alternation a driving and a retracting motor-magnet of respectively completely reverse polarity and having a half-part of their fields superposed in respect to the successive positions thereof; and diverter-mechanism for diverting the current alternately from one field to the other, said mechanism being controlled by the reciprocating core; substantially as specified. 80
14. In an electric hammer, in combination: a reciprocatory magnetic percussion-core reciprocating within three axially alined and contiguous coils adapted to be alternately energized in series in pairs; connections of one polarity leading to the free ends of the end coils, and of opposite polarity tapping the connections between the middle and end coils, whereby the coils may be energized in pairs to produce in alternation a driving and a retracting motor-magnet of respectively completely reverse polarity and having a half-part of their fields superposed in respect to the successive positions thereof; and automatic diverter-mechanism, self-contained in the device, for diverting the current alternately from one field to the other, said mechanism being controlled by the reciprocating core; substantially as specified. 90
15. In an electric hammer, in combination: a reciprocatory magnetic percussion-core reciprocating within axially alined and contiguous coils; connections whereby the coils may be energized to produce in alternation a driving and a retracting motor-magnet of respectively completely reverse polarity and having a part of their fields superposed in respect to the successive positions thereof; and automatic diverter-mechanism, self-contained in the device, for diverting the current alternately from one field to the other, said mechanism being mechanically controlled by the reciprocating core; substantially as specified. 100
16. In an electric hammer, in combination: a reciprocatory magnetic percussion-core reciprocating within axially alined and contiguous coils; connections whereby the coils may be energized to produce in alternation a driving and a retracting motor-magnet of respectively completely reverse polarity and having a part of their fields superposed in respect to the successive positions thereof; and automatic diverter-mechanism, self-contained in the device, for diverting the current alternately from one field to the other, said mechanism being mechanically controlled by the reciprocating core; substantially as specified. 110
17. In an electric hammer, in combination: a reciprocatory magnetic percussion-core reciprocating within three axially alined and contiguous equal coils adapted to be alternately energized in series in pairs; connections of one polarity leading to the free ends of the end coils, and of opposite polarity tapping the connections between the middle and end coils, whereby the coils may be energized in pairs to produce in alternation a driving and a retracting motor-magnet of respectively completely reverse polarity and having a half-part of their fields superposed in respect to the successive positions thereof; and automatic diverter-mechanism, self-contained in the device, for diverting the current alternately from one field to the other, said mechanism being mechanically controlled by the reciprocating core and having an oscillating diverter adapted to be shifted to the alternately active contacts; substantially as specified. 120
18. In an electric hammer, in combination: a reciprocatory magnetic percussion-core reciprocating within three axially alined and contiguous coils; connections whereby the coils may be energized to produce in alternation a driving and a retracting motor-magnet of respectively completely reverse polarity and having a part of their fields superposed in respect to the successive positions thereof; and automatic diverter-mechanism, self-contained in the device, for diverting the current alternately from one field to the other, said mechanism being mechanically controlled by the reciprocating core and having an oscillating diverter adapted to be shifted to the alternately active contacts; substantially as specified. 130
19. In an electric hammer, in combination: a reciprocatory magnetic percussion-core reciprocating within three axially alined and contiguous coils; a jacketing of magnetic material, constituting all of said

- coils ironclad; connections whereby the coils may be energized in pairs to produce in alternation a driving and a retracting motor-magnet of respectively completely reverse 5 polarity and having a half-part of their fields superposed in respect to the successive positions thereof; a blow-transmitter of magnetic material at the impact end of the driving magnet, constituting said magnet 10 of stopped type, the retracting magnet being of open type; and automatic diverter-mechanism, self-contained in the device, for diverting the current alternately from one field to the other; substantially as specified.
- 15 20. In an electric hammer, in combination: a reciprocating magnetic percussion-core reciprocating within axially alined and contiguous coils; a jacketing of magnetic material, constituting said coil ironclad; 20 connections, insulated from the core, whereby the coils may be energized to produce in alternation a driving and a retracting motor-magnet, respectively fully energized instantly upon each reversal; a blow-trans- 25 mitter of magnetic material at the impact end of the driving magnet, constituting said magnet of stopped type adapted to augment the impact of the core, the retracting magnet being of open type adapted to check the 30 retraction-stroke of the core; and automatic diverter-mechanism, self-contained in the device, for diverting the current alternately from one field to the other, said mechanism being mechanically controlled by the recip- 35 roating core and having a diverter adapted to be shifted to the alternately active contacts extraneous to said core; substantially as specified.
21. In an electric hammer, in combina- 40 tion: a reciprocating magnetic percussion-core reciprocating within three axially alined and contiguous coils adapted to be alternately energized in series in pairs; connec- 45 tions of one polarity leading to the free ends of the end coils, and of opposite polarity tapping the connections between the middle and end coils, whereby the coils may be energized in pairs to produce in alternation a driving and a retracting motor-mag- 50 net of reverse polarity and having a half-part of their fields superposed in respect to the successive positions thereof; and automatic diverter-mechanism, self-contained in the device, for diverting the current alter- 55 nately from one field to the other, said mech- anism being controlled by the reciprocating core and having a diverter adapted to be shifted to the alternately active contacts and to span the space between them; substan- 60 tially as specified.
22. In an electric hammer, in combina- 65 tion: a reciprocating magnetic percussion-core reciprocating within axially alined and contiguous coils; connections whereby the coils may be energized to produce in alterna- 70 tion a driving and a retracting motor-magnet, and automatic diverter-mechanism, self-contained in the device, for diverting the current alternately from one magnet field to the other, said mechanism being mechanically controlled by the reciprocating core and having an oscillating diverter adapted to be shifted to the alternately active contacts, and a stop-rod coöperating with said diverter and the core; substan- 75 tially as specified.
23. In an electric hammer, in combina- 80 tion: a reciprocating magnetic percussion-core reciprocating within axially alined and contiguous coils; connections whereby the coils may be energized to produce in alternation a driving and a retracting motor-magnet; and automatic diverter-mechanism, self-contained in the device, for diverting the current alternately from one magnet field to the other, said mechanism being mechanically controlled by the reciprocating core and having a diverter adapted to be shifted to the alternately active contacts, and a stop-rod coöperating with said di- 85 verter and freely inserted longitudinally through the core and provided with opposed stops; substantially as specified.
24. In an electric hammer, in combina- 90 tion: a reciprocating magnetic percussion-core reciprocating within axially alined and contiguous coils; connections whereby the coils may be energized to produce in alternation a driving and a retracting motor-magnet; and automatic diverter-mechanism, self-contained in the device, for diverting the current alternately from one magnet field to the other, said mechanism being mechani- 95 cally controlled by the reciprocating core and having an oscillating diverter adapted to be shifted to the alternately active contacts, and a stop-rod coacting with said di- 100 verter and the core and provided with op- posed cushioning means to cushion the move- 105 ment of said stop rod; substantially as specified.
25. In an electric hammer, in combina- 110 tion: a reciprocating magnetic percussion-core reciprocating within axially alined and contiguous coils; connections whereby the coils may be energized to produce in alternation a driving and a retracting motor-magnet; and automatic diverter-mechanism, self-contained in the device, for diverting the current alternately from one magnet field to the other, said mechanism being mechani- 115 cally controlled by the reciprocating core and having a diverter adapted to be shifted to the alternately active contacts, and a stop-rod coöperating with said diverter and freely inserted longitudinally through the core and provided with opposed stops and with op- 120 posed cushioning means to cushion the move- 125 ment of said stop-rod; substantially as specified.

26. In an electric hammer, in combination: a reciprocating magnetic percussion-core within axially alined and contiguous coils; connections whereby the coils may be energized to produce in alternation a driving and a retracting motor-magnet; and automatic diverter-mechanism, self-contained in the device, for diverting the current alternately from one field to the other, 5 said mechanism being controlled by the reciprocating core and having a diverter adapted to be shifted to the alternately active contacts, and a spring-trigger mechanism for snap-shifting the diverter and for 10 detaining the diverter at either limit of its throw; substantially as specified.
27. In an electric hammer, in combination: a reciprocating magnetic percussion-core within axially alined and contiguous 15 coils; connections whereby the coils may be energized to produce in alternation a driving and a retracting motor-magnet; and automatic diverter-mechanism, self-contained in the device, for diverting the current alternately from one field to the other, 20 said mechanism being controlled by the reciprocating core and having a diverter adapted to be shifted to the alternately active contacts, and a spring-trigger mechanism for snap-shifting the diverter and for 25 detaining the diverter at either limit of its throw; substantially as specified.
28. In an electric hammer, in combination: a reciprocating magnetic percussion-core within axially alined and contiguous 30 coils; connections whereby the coils may be energized to produce in alternation a driving and a retracting motor-magnet; and automatic diverter-mechanism, self-contained in the device for diverting the current alternately from one field to the other, 35 said mechanism being controlled by the reciprocating core and having a diverter adapted to be shifted to the alternately active contacts, and a spring-trigger mechanism for snap-shifting the diverter; substantially as 40 specified.
29. In an electric hammer, in combination: a reciprocating magnetic percussion-core within axially alined and contiguous 45 coils; connections whereby the coils may be energized to produce in alternation a driving and a retracting motor-magnet; and automatic diverter-mechanism, self-contained in the device for diverting the current alternately from one field to the other, 50 said mechanism being controlled by the reciprocating core and having a diverter adapted to be shifted to the alternately active contacts, and a spring-trigger mechanism for detaining the diverter at either limit of its throw; substantially as 55 specified.
30. In an electric hammer, in combination: a reciprocating magnetic percussion-core within axially alined and contiguous 60 coils; connections whereby the coils may be energized to produce in alternation a driving and a retracting motor-magnet; and automatic diverter-mechanism, self-contained in the device, for diverting the current alternately from one field to the other, 65 said mechanism being controlled by the reciprocating core and having a diverter adapted to be shifted to the alternately active contacts, and a spring-trigger mechanism for snap-shifting the diverter and for 70 detaining the diverter at either limit of its throw; substantially as specified.
31. In an electric hammer, in combination: a reciprocating magnetic percussion-core within axially alined and contiguous 75 coils; connections whereby the coils may be energized to produce in alternation a driving and a retracting motor-magnet; and automatic diverter-mechanism, self-contained in the device, for diverting the current alternately from one field to the other, 80 said mechanism being mechanically controlled by the reciprocating core and having a diverter adapted to be shifted to the alternately active contacts, and a stop-rod co-operating with said diverter and for 85 detaining the diverter at either limit of its throw; substantially as specified.
32. In an electric hammer, in combination: a reciprocating magnetic percussion-core within axially alined and contiguous 90 coils; connections whereby the coils may be energized to produce in alternation a driving and a retracting motor-magnet; and automatic diverter-mechanism, self-contained in the device, for diverting the current alternately from one field to the other, 95 said mechanism being mechanically controlled by the reciprocating core and having a diverter adapted to be shifted to the alternately active contacts, and a stop-rod co-operating with said diverter and freely inserted longitudinally through the core and provided with opposed stops and with opposed cushioning means to cushion the movement of said stop-rod, and a mechanism for snap-shifting the diverter and for detaining the diverter at either limit of its throw; substantially as 100 specified.
33. In an electric hammer, in combination: a reciprocating magnetic percussion-core within axially alined and contiguous 105 coils; connections whereby the coils may be energized to produce in alternation a driving and a retracting motor-magnet; and automatic diverter-mechanism, self-contained in the device, for diverting the current alternately from one field to the other, 110 said mechanism being mechanically controlled by the reciprocating core and having an oscillating diverter adapted to be shifted to the alternately active contacts, and a spring-trigger mechanism for snap-shifting the diverter and for detaining the diverter at either limit of its throw; substantially as 115 specified.
34. In an electric hammer, in combination: a reciprocating magnetic percussion-core within axially alined and contiguous 120 coils; connections whereby the coils may be energized to produce in alternation a driving and a retracting motor-magnet; and automatic diverter-mechanism, self-contained in the device, for diverting the current al-

- ternately from one field to the other, said mechanism being mechanically controlled by the reciprocating core and having an oscillating diverter adapted to be shifted to the alternately active contacts, and a stop-rod coöperating with said diverter and freely inserted longitudinally through the core and provided with opposed stops and with opposed cushioning means to cushion the movement of said stop-rod, and a mechanism for snap-shifting the diverter and for detaining the diverter at either limit of its throw: substantially as specified.
34. In an electric hammer, in combination: a reciprocatory magnetic percussion-core within axially alined and contiguous coils; connections whereby the coils may be energized to produce in alternation a driving and a retracting motor-magnet; and automatic diverter-mechanism, self-contained in the device, for diverting the current alternately from one magnet to the other, said mechanism being mechanically controlled by the reciprocating core and having an oscillating diverter adapted to be shifted to the alternately active contacts, and a stop-rod coöperating with said diverter and the core and provided with opposed cushioning means to cushion the movement of said stop-rod, and a spring-trigger mechanism for snap-shifting the diverter and for detaining the diverter at either limit of its throw; substantially as specified.
35. In an electric hammer, in combination: a reciprocatory magnetic percussion-core reciprocating within axially alined and contiguous coils; connections whereby the coils may be energized to produce in alternation a driving and a retracting motor-magnet; automatic diverter-mechanism, self-contained in the device, for diverting the current alternately from one magnet to the other, said mechanism being mechanically controlled by the reciprocating core and having a diverter adapted to be shifted to the alternately active contacts; and pressure-controlled means, actuated by the mere pressing of the hammer to its work, for graduating the impact of the core upon the blow-transmitter; substantially as specified.
36. In an electric hammer, in combination: a reciprocatory magnetic percussion-core reciprocating within axially alined and contiguous coils; connections whereby the coils may be energized to produce in alternation a driving and a retracting motor-magnet; automatic diverter-mechanism, self-contained in the device, for diverting the current alternately from one magnet to the other, said mechanism being mechanically controlled by the reciprocating core and having a diverter adapted to be shifted to the alternately active contacts; and optionally operable pressure-controlled means,
- actuated by the mere pressing of the hammer to its work, for graduating the impact of the core upon the blow-transmitter; substantially as specified.
37. In an electric hammer, in combination: a reciprocating magnetic percussion-core reciprocating within axially alined and contiguous coils; connections whereby the coils may be energized to produce in alternation a driving and a retracting motor-magnet; automatic diverter-mechanism, self-contained in the device, for diverting the current alternately from one magnet to the other, said mechanism being mechanically controlled by the reciprocating core and having a diverter adapted to be shifted to the alternately active contacts; and optionally operable pressure-controlled means, actuated by the mere pressing of the hammer to its work, for graduating the impact of the core upon the blow-transmitter, said means including a slidably movable member, for approximating the point of impact and the diverter-mechanism, and a coil spring normally holding the parts in such relation as to give the lighter impact but compressibly yielding to permit heavier impact; substantially as specified.
38. In an electric hammer, in combination: a reciprocatory magnetic percussion-core reciprocating within axially alined and contiguous coils; connections whereby the coils may be energized to produce in alternation a driving and a retracting motor-magnet; automatic diverter-mechanism, self-contained in the device, for diverting the current alternately from one magnet to the other, said mechanism being mechanically controlled by the reciprocating core and having a diverter adapted to be shifted to the alternately active contacts; and optionally operable pressure-controlled means, actuated by the mere pressing of the hammer to its work, for graduating the impact of the core upon the blow-transmitter, said means including a slidably movable member and a coil spring normally holding the parts in such relation as to give the lighter impact but compressibly yielding to permit heavier impact; substantially as specified.
39. In an electric hammer, in combination: a reciprocatory magnetic percussion-core reciprocating within axially alined and contiguous coils; connections whereby the coils may be energized to produce in alternation a driving and a retracting motor-magnet; automatic diverter-mechanism self-contained in the device, for diverting the current alternately from one magnet to the other, said mechanism being mechanically controlled by the reciprocating core and having a diverter adapted to be shifted to the alternately active contacts; and optionally operable pressure-controlled means,

actuated by the mere pressing of the hammer to its work, for graduating the impact of the core upon the blow-transmitter, said means including a movable member and a 5 spring normally holding the parts in such relation as to give the lighter impact but

yielding to permit heavier impact; substantially as specified.
